Filed May 29, 1959, Ser. No. 816,876

7 Claims. (Cl. 232—17)

This invention relates to an improved mail box of the type having a stationary section and a movable section which is movable relative to the stationary section to expose and provide easy access to mail present in the box.

The primary object of the invention is to provide a simple, more efficient and more practical mail box of the character indicated which is easier to operate and which can be made in attractive and durable forms at low cost, from a variety of available materials, including wood, metals and plastics.

Another object of the invention is to provide a weather-proof mail box of the character indicated above wherein the movable section is spring-retumed to mail-enclosing position relative to the stationary section from operated position.

A further object of the invention is to provide a mail box of the character indicated above which, other than the return spring means and a hinged cover or lid, is composed of only two parts, namely the stationary section and the movable section, which can be monolithic forms.

Other important objects and advantageous features of the invention will be apparent from the following description and the accompanying drawings, wherein, for purposes of illustration only, a specific form of the invention is set forth in detail.

In the drawings:

Figure 1 is a front perspective view of a mail box of the invention, in unoperated condition;

Figure 2 is a similar view, showing the lid open and the movable section depressed to expose mail when present in the stationary section;

Figure 3 is an enlarged horizontal section taken on the line 3—3 of Figure 1;

Figure 4 is an enlarged vertical transverse section taken on the line 4—4 of Figure 1; and

Figure 5 is a vertical longitudinal section taken on the line 5—5 of Figure 4.

Referring in detail to the drawings, wherein like numerals designate like parts throughout the several views, the illustrated mail box comprises a stationary section 10, a movable section 12, and retracting spring means 14.

The stationary section 10 is vertically elongated and of substantially U-shaped horizontal cross section, as seen in Figure 3, and comprises a back wall 16 and two forwardly and right-angularly extending side walls 18 which are inset from the side edges 20 of the back wall. The side walls 18 have straight forward edges 22 which are parallel to the back wall 16. On the laterally outward sides of the side walls 18 are vertical, rectangular cross section ribs 24, which are parallel to the back wall 16 and are spaced forwardly therefrom at distances about half of the width of a side wall. Vertical grooves 26, aligned with the ribs 24, are formed in the laterally inward sides of the side walls 18, in the lower halves thereof and open through the lower edges 28 of the side walls and through related parts of a bottom wall 30 which extends between and is fixed to the side walls 18 and the back wall 16. The bottom wall 30 has a free forward

2

edge 32 which is flush with the forward edges 22 of the side walls.

As is apparent in Figures 2 and 4, the side walls 18 have straight, forwardly and downwardly angled or declining upper edges 34, and these edges 34 and the upper edge 36 of the back wall 16 define an open top for the stationary section 10, which is normally closed by a lid or cover 38 which is hinged, as indicated at 40, at the forward edge of a strip 42 fixed in suitable manner upon the upper edge 36 of the back wall. As seen in Figures 2 and 5, the strip 42 and the lid 38 are wider than the stationary section 10 so as to close not only the upper end of the stationary section 10, but also the upper end of the movable section 12, in the elevated position of the movable section 12.

It is to be noted that in the depressed position of the movable section 12, the lid 38 can remain in closing relation to the upper end of the stationary section, in which case the lid 38 serves as a rain and snow shield for the depressed upper end of the movable section 12.

The movable section 12 is vertically elongated and of U-shaped horizontal cross section, as seen in Figure 3, and comprises a front wall 44, which is preferably made relatively thin so as to reduce the weight and the overall cross section of the mail box, and which is of the same width as the stationary section back wall 16, and bears slidably against the forward edges 22 of the stationary section side walls 18. The front wall 44 is of a height to put its bevelled upper edge 46 flush with the forward lower ends of the declining upper edges 34 of the stationary section side walls 18, when the movable section 12 is in its upwardly retracted, normal position, as shown in Figure 4 in full lines, wherein the lid 38 can rest upon and seal the upper edge 46 of the front wall, as well as the upper edges of the side walls.

The movable section has side walls 48 extending rearwardly from side edge portions of the front wall 44 and bearing slidably against the laterally outward sides of the stationary section side walls 18, and are provided with vertical grooves 50 to conformably and slidably receive the ribs 24 on the stationary section side walls 18, so as to assemble the movable section 12 to the stationary section 10 and confine the same to vertical sliding movement thereon. The side walls 48 have forwardly declining upper edges 52 which are positioned and angled to be flush with the upper edges of the stationary section side walls 18, in the retracted position of the movable section, and to be engaged and sealed by the lid 38.

Further sliding support of the movable section 12 on the stationary section 10 is provided by reduced width laterally inwardly offset, vertical ribs 54 on the rear edges of the movable section side walls 48, slidably engaged in conformably shaped vertical grooves 56 formed in the stationary section back wall 16, outside of its side walls 18, and by the sliding engagement of resultant outwardly offset, forwardly extending vertical ribs 58 on the back wall 16 in the resultant outwardly off-set vertical grooves 60 in the movable section side walls 48.

A viewing opening 62 is provided centrally in the movable section front wall 44, to expose the presence of mail in the mail box, and is weather-sealed by a glass 64 engaged with the front side of the front wall 44 and confined in a recess 66 provided therefor in the rear side of a retaining plate 68 which is fixed, in suitable manner to the front side of the front wall 44, and has an opening 70 registered with the viewing opening 62 and the glass 64. The retaining plate 68 is preferably of ornamental shape and execution, so as to form a decoration for the mail box.

For operating the movable section 12, a pendant bail handle 72 is affixed, as indicated at 74, to the under side of its bottom wall 73 of the movable section, at a point

toward the forward edge thereof, so that the handle 72 can be readily grasped and pulled downwardly, so as to slide the movable section 12 downwardly relative to the stationary section, against the resistance of retracting spring means 14, to a depressed mail-exposing position.

The retracting or elevating spring means 14 preferably takes the form of vertical helical contractile springs 76 which are located in the stationary section side wall grooves, and are anchored at their upper ends, as indicated at 78, at the upper ends of these grooves, and are secured at their lower ends, as indicated at 80, to the bottom wall 73 of the movable section 12. The movable section 12 is stopped in its normal elevated position, as it is elevated by the spring means, by engagement of the movable section bottom wall 73 with the bottom wall 30 of the stationary section 10.

Obviously, pulling the movable section 12 downwardly relative to the stationary section 10, and holding the position, exposes the open front of the stationary section, as shown in Figure 2, so that any mail present in the mail box is exposed, above the movable section, and can be readily grasped and removed from the mail box, without the usual difficulties of having to reach into the mail box, whereat the handle 72 is released and the springs 76 elevate the movable section to its normal position. It will be understood that mail is deposited in the mail box by the mail man through the open top of the stationary section 10, the lid 38 being held open, and that no other operation of the mail box is required of the mail man.

For extra capacity and convenience, especially for large pieces of mail, such as newspapers and magazines, the movable section 12 is provided with a pair of laterally spaced forwardly and upwardly opening hooks 82, which comprise vertical bars 84 secured at their upper ends, as indicated at 86, to the movable section bottom wall 73 near the rear edge thereof, and forwardly reaching crooks 88 on the lower ends of the bars 84. The hooks 82 are located entirely beneath the movable section, so that articles placed in the hooks are shielded from rain and snow by the mail box.

The stationary section back wall 16 is provided with vertically spaced screw holes 92, through which screws 94 can be readily passed and screwed into a suitable vertical mail box support, such as a house wall 96.

It will be observed that the simple uncomplicated structures of the stationary and movable sections lend themselves to easy and economical mass manufacture as monolithic forms, such as plastic moldings.

While there has been shown and described herein a preferred form of the invention, it is to be understood that the invention is not necessarily confined thereto, and that any change or changes in the structure of and in the relative arrangements of components thereof are contemplated as being within the scope of the invention as defined by the claims appended hereto.

What is claimed is:

1. A mail box comprising a vertical stationary section having a back wall, sidewalls, a bottom wall, an open upper end and an open front, a vertical movable section having sidewalls, a bottom wall, a front wall, an open upper end and an open rear, said movable section being slidably telescoped on the stationary section with its front wall in closure relation to the open front of the stationary section and with its bottom wall beneath the bottom wall of the stationary section, a handle on the movable section, retracting spring means acting between and secured to the sections for elevating the movable section to its normal elevated position on the stationary section wherein its bottom wall is in stop engagement with the lower end of the stationary section, said stationary section back wall having side edge portions extending laterally outwardly beyond the side walls of the stationary section, sidewalls of the movable section bearing slidably against the laterally outward sides of the stationary section.

section side walls and against said side edge portions, the side walls of the sections having interengaged vertical rib and groove means assembling the movable section to the stationary section.

5 2. A mail box comprising a vertical stationary section having a back wall, sidewalls, a bottom wall, an open upper end and an open front, a vertical movable section having sidewalls, a bottom wall, a front wall, an open upper end and an open rear, said movable section being 10 slidably telescoped on the stationary section with its front wall in closure relation to the open front of the stationary section and with its bottom wall beneath the bottom wall of the stationary section, a handle on the movable section, retracting spring means acting between and secured to the sections for elevating the movable section to its normal elevated position on the stationary section wherein its bottom wall is in stop engagement with the lower end of the stationary section, said stationary section back wall having side edge portions extending 15 laterally outwardly beyond the side walls of the stationary section, sidewalls of the movable section bearing slidably against the laterally outward sides of the stationary section side walls and against said side edge portions, the side walls of the sections having interengaged vertical rib and groove means assembling the movable section to the stationary section, said side edge portions of the stationary section back wall having forwardly opening vertical grooves therein and the movable section side walls having rearwardly extending vertical ribs slidably confined in the grooves.

20 3. A mail box comprising a vertical stationary section having a back wall, sidewalls, a bottom wall, an open upper end and an open front, a vertical movable section having sidewalls, a bottom wall, a front wall, an open upper end and an open rear, said movable section being 25 slidably telescoped on the stationary section with its front wall in closure relation to the open front of the stationary section and with its bottom wall beneath the bottom wall of the stationary section, a handle on the movable section, retracting spring means acting between and secured to the sections for elevating the movable section to its normal elevated position on the stationary section wherein its bottom wall is in stop engagement with the lower end of the stationary section, said stationary section back wall having side edge portions extending laterally 30 outwardly beyond the side walls of the stationary section, sidewalls of the movable section bearing slidably against the laterally outward sides of the stationary section side walls and against said side edge portions, the side walls of the sections having interengaged vertical rib and groove means assembling the movable section to the stationary section, said retracting spring means comprising vertical 35 grooves in the laterally inward sides of the stationary section side walls and openings in the stationary section bottom thereat, and vertical contractile springs positioned 40 in the grooves and stretched between upper parts of these grooves and the bottom wall of the movable section.

4. A mail box comprising a stationary section and a movable section, said stationary section consisting of a 45 vertical back wall securable to a support, forwardly extending vertical sidewalls, and a bottom wall extending between the sidewalls and the back wall, said sidewalls having forward edges, said movable section consisting of a vertical front wall, rearwardly extending vertical sidewalls, and a bottom wall extending between its sidewalls and its front wall, the movable section sidewalls having 50 rear edges, said movable section being telescoped with said stationary section, with the bottom wall of the movable section disposed below the bottom wall of the stationary section, the sides of the sidewalls of the sections being in sliding engagement, interengaged rib and groove means on the facing sides of the sidewalls slidably mounting the movable section on the stationary section, and elevating spring means connected between the stationary 55 section and the movable section, the sidewalls of the

movable section being positioned laterally outwardly of the sidewalls of the stationary section, the sidewalls of the stationary section having laterally inward sides formed with vertical grooves, and said spring means comprising vertical coil springs disposed in said grooves and connected in stretched condition, at their upper ends to the stationary section sidewalls and at their lower ends to the bottom wall of the movable section.

5. A mail box comprising a stationary section and a movable section, said stationary section consisting of a vertical back wall securable to a support, forwardly extending vertical sidewalls, and a bottom wall extending between the sidewalls and the back wall, said sidewalls having forward edges, said movable section consisting of a vertical front wall, rearwardly extending vertical sidewalls, and a bottom wall extending between its sidewalls and its front wall, the movable section sidewalls having rear edges, said movable section being telescoped with said stationary section, with the bottom wall of the movable section disposed below the bottom wall of the stationary section, the sides of the sidewalls of the sections being in sliding engagement, interengaged rib and groove means on the facing sides of the sidewalls slidably mounting the movable section on the stationary section, and elevating spring means connected between the stationary section and the movable section, the sidewalls of the movable section being positioned laterally outwardly of the sidewalls of the stationary section, the back wall of the stationary section having side edge portions extending laterally outwardly beyond the sidewalls of the stationary section, said edge portions having forwardly opening vertical guide grooves, and the sidewalls of the movable section having their rear edges slidably engaged in the guide grooves.

6. A mail box comprising a stationary section and a movable section, said stationary section consisting of a vertical back wall securable to a support, forwardly extending vertical sidewalls, and a bottom wall extending between the sidewalls and the back wall, said sidewalls having forward edges, said movable section consisting of a vertical front wall, rearwardly extending vertical sidewalls, and a bottom wall extending between its sidewalls and its front wall, the movable section sidewalls having rear edges, said movable section being telescoped with said stationary section, with the bottom wall of the movable section disposed below the bottom wall of

the stationary section, the sides of the sidewalls of the sections being in sliding engagement, and elevated spring means connected between the stationary section and the movable section, the sidewalls of the movable section being positioned laterally outwardly of the sidewalls of the stationary section, the sidewalls of the stationary section having laterally inward sides formed with vertical grooves, and said spring means comprising vertical coil springs disposed in said grooves and connected in stretched condition, at their upper ends to the stationary section sidewalls and at their lower ends to the bottom wall of the movable section.

7. A mail box comprising a stationary section and a movable section, said stationary section consisting of a vertical back wall securable to a support, forwardly extending vertical sidewalls, and a bottom wall extending between the sidewalls and the back wall, said sidewalls having forward edges, said movable section consisting of a vertical front wall, rearwardly extending vertical sidewalls, and a bottom wall extending between its sidewalls and its front wall, the movable section sidewalls having rear edges, said movable section being telescoped with said stationary section, with the bottom wall of the movable section disposed below the bottom wall of the stationary section, the sides of the sidewalls of the sections being in sliding engagement, and elevating spring means connected between the stationary section and the movable section, the sidewalls of the movable section being positioned laterally outwardly of the sidewalls of the stationary section, the back wall of the stationary section having side edge portions extending laterally outwardly beyond the sidewalls of the stationary section, said edge portions having forwardly opening vertical guide grooves, and the sidewalls of the movable section having rear edges slidably engaged in the guide grooves.
